[57] CLAIM

The ornamental design for a plastic pipe heat fusion
tool, as shown and described.

DESCRIPTION

FIG. 1 is a front elevational view of the design of the
plastic pipe heat fusion tool of the present invention.
FIG. 2 is an elevational view of one end of the design of
FIG. 1.

FIG. 3 is a top plan view of the design of FIG. 1.
FIG. 4 is an elevational view of the opposite end of
FIG. 1.

FIG. 5 is a rear elevational view of the design of FIG.
1.

FIG. 6 is a bottom plan view of the design of FIG. 1.
